UNITED STATES PATENT OFFICE

NICHOLAS H. STUART, OF BUFFALO, NEW YORK, ASSIGNOR TO REMINGTON RAND INC.,
OF BUFFALO, NEW YORK

LOOSE LEAF BINDER

Application filed March 13, 1929. Serial No. 346,592.

The invention relates to temporary binders and has particular relation to binders of the loose leaf type in which the cover members may be adjusted toward and away from one another in order to clamp stacks of pages of varying numbers therebetween or to permit of the quick removal of the pages therefrom or the insertion of additional pages therein.

One of the objects of the present invention is to provide a binder of the character described in which means are provided on one of the cover members for adjusting the covers predetermined distances apart in order to accommodate pages arranged in a group of a certain thickness and in which the other cover member is provided with an auxiliary adjusting mechanism by means of which the covers may be clamped together various distances apart within the range determined by the first mentioned adjustment, thus rendering it possible to accommodate a large number of pages and to securely bind the pages in position regardless of the thickness of the group thereof.

Another object of the invention is to provide a simple and efficient mechanism for clamping a stack or group of pages between the covers of a binder and which embodies a single member operable with one hand for both releasing the covers from clamped position and for moving them relative to each other in order to permit of the quick and easy insertion or removal of pages from the binder.

A further object of the invention is to provide a novel locking mechanism for a binder of the character described which is simple in construction and arrangement and which may be assembled and disassembled with a minimum of time and effort.

Other objects of the invention will appear from the following specification and appended claims.

In the accompanying drawing,

Fig. 1 is a plan view of a loose leaf binder with the covers thereof in an open position and with portions broken away to more clearly illustrate the improved adjusting and locking mechanism.

Fig. 2 is an enlarged sectional view of a

portion of the binder taken on line 2—2 of Fig. 1, the covers being in closed position.

Fig. 3 is an enlarged fragmentary plan view of the improved locking mechanism.

Fig. 4 is a transverse sectional view taken one line 4—4 of Fig. 3.

Fig. 5 is a transverse sectional view taken on line 5—5 of Figure 1, but with the locking means disengaged.

Fig. 6 is an enlarged detail showing the central portion of the anchor member in perspective.

Referring to the drawing, a binder constructed in accordance with the present invention is shown as comprising a pair of cover members 1 and 2 each of which includes a rectangular frame 3 having sheet metal plates 4 and 5 secured to the inner and outer sides thereof by rivets 6. Channel members 7 are secured to the adjacent edges of the cover members 1 and 2 respectively and are formed with ear portions 8 pivotally connected to coat with members 9 provided on each of a pair of clamping bars 10. These bars are provided with apertures 11 adapted to receive the ends of oppositely extending posts 12 which are carried by a pair of retaining bars 13. These bars directly engage the opposite sides of a group of pages 14 and the posts 12 of each of these bars extend through a series of registering perforations 15 formed in the pages.

An adjusting bar 17 extends transversely with respect to the cover 1 between the plates 4 and 5 and is provided with a guide-way 18 for slidble engagement with a ratchet bar 19 which is secured to the cover 1 between the plates 4 and 5. A pair of flexible straps or thongs 20 are each secured to one end of the adjusting bar 17 by a clip 21, (Fig. 1), and extend through the channel members 8 on the cover members 1 and 2 and slots 22 provided in the retaining bars 13 and are fixed at their other ends to a cross bar or anchor member 23. The stack or group of pages 14 is preferably notched transversely as indicated at 24 in order to receive the thongs 20 where they cross from cover to cover back of the stack. The central portion of the anchor member 23 is struck down adjacent to

each edge thereof to provide a pair of straps 25 for slidable engagement with a rail 26 which is mounted on the cover member 2 and which is formed with a plurality of apertures 27 arranged at intervals longitudinally thereof. A spring plate or leaf spring 28 is fixed at one end to the member 23 and carries a pin 29 at its other end which is adapted to project through an aperture 30 in the bar 23 for engagement with the apertures 27 in the rail 26.

The spring 28 is flexed outwardly away from the plane of the cover in order to retract the pin 29 from locking engagement with the rail 26 by means of a bifurcated lever 31 the arms 32 of which straddle the spring 28 and are provided with extensions at their ends as indicated at 33 for pivotal engagement with a pair of slots 34 formed in the member 23. The arms 32 of the lever are connected by a portion 35 which extends transversely between the spring 28 and the member 23 and is adapted to bear against the spring 28 and to raise the same when the lever 31 is swung outwardly.

The adjusting bar 17 is locked in an adjusted position in order to maintain the clamping bars 10 together by means of a pawl 36 which is pivotally mounted as at 37 upon the bar 17 and which is yieldably urged into engagement with the ratchet bar 19 by means of a spring 38. A plate 39 is fixed to the pawl 36 and is formed with a projection or finger 40 which projects into a slot or recess 41 formed in the guideway 18 and overlies the ratchet bar 19 for engagement by a pin 42. This pin extends transversely through a stud or rotatable member 43 which is rotatably mounted in the bar 17 and guide plate 18 and is provided with an angular shoulder or collar 44, (Fig. 4), to prevent the upward displacement thereof. The stud 43 is slotted as at 45 to receive a handle 46 which is pivotally mounted on the pin 42 and which extends through a slot 47 formed in the plate 4 of the cover. The handle 46 is provided with a shoulder 48 for engagement with the stud to arrest the upward or outward swinging movement of the handle 46 in a position substantially perpendicular to the plane of the cover. A leaf spring 49 bears against the lower extremities of the handle 46 and tends to normally maintain the handle in an inoperative position flat against the cover.

When it is desired to release the covers to permit of the insertion or removal of pages to or from the binder the handle 46 is first swung upwardly about the pin 42 against the action of the spring 49 to the position shown in Fig. 4. The handle is then turned about an axis substantially normal to the plane of the cover thus causing the pin 42 to bear against the finger 40 of the plate 39 thus releasing the pawl 36 from engagement with

the ratchet bar 19 against the action of the spring 38. As soon as the ratchet is released from the rack bar 19 the handle 46 may be employed to move the adjusting bar 17 and the parts carried thereby longitudinally of the ratchet bar 19 in order to release the group of pages from the binder or to clamp it more firmly in position. It will be noted that the shoulder 48 on the handle forms with the stud 43 a solid abutment permitting considerable force to be exerted on the handle in tightening the adjusting bar and the thongs in an adjusted position.

From the foregoing it will be apparent that a very simple and efficient mechanism is provided by means of which the anchor bar may be adjusted to a position which permits the cover members to be separated a predetermined distance in order to receive a certain number of pages and the adjusting bar then adjusted to maintain the covers varying distances apart within the range determined by the position of the anchor bar. Thus, when the number of pages in the group shall reach the limit of adjustment of the adjusting bar 17 the anchor bar 23 is first advanced inwardly toward the hinged edge of the cover to another position on the rail 25. The adjusting bar 17 may then be slid outwardly along the ratchet bar 19 toward the outer edge of the cover 1 to a position where it may be again employed to clamp the covers together as the pages still further increase in number. These adjustments may be repeated until the capacity of the binder reaches its limit at which time both the anchor bar 23 and the adjusting bar 17 will occupy positions adjacent to the clamping bars 10 to which the cover members 1 and 2 are hinged. By means of the above-described construction a binder may be provided having a very large capacity and in which either a large group of pages or a relatively few pages may be quickly inserted in or removed from the binder and the covers readjusted to securely clamp a group of pages the thickness of which have been thus increased or decreased.

In practice the adjustment of the anchor bar 23 is never disturbed except when the capacity of the binder is materially increased or decreased. The adjusting bar 17 is employed when it is desired to remove the entire contents of the binder as is the custom for tabulating or other bookkeeping purposes and is utilized to apply the necessary degree of compression when the contents of the binder is replaced. It will thus be seen that the adjustment bar 17 and the anchor bar 23 are not counter-parts but each has its particular and independent function.

The invention may be modified in construction and arrangement without departing from the spirit and scope of the invention defined in the appended claims.

What is claimed is:

1. In a temporary binder the combination of a pair of cover members, a rail mounted on one of said cover members and having a plurality of apertures formed therein, a cross-bar slidably mounted on said rail and provided with a pair of spaced slots, means connecting said cross-bar to the other of said cover members, a leaf spring carried by said cross-bar, a pin carried by said leaf spring for engagement with said apertures, and a bifurcated lever having spaced extensions adapted to removably engage in the slots provided in said cross-bar to mount the lever for hinging movement relative the cross-bar and a transverse connecting portion adapted to engage said leaf spring and flex the same to retract said pin from engagement with said apertures, said spring retaining the offset portions of the lever in engagement in the slots of the cross-bar.
2. In a temporary binder the combination of a pair of cover members, a rail mounted on one of said cover members and having a plurality of apertures formed therein, an anchor bar slidably mounted for longitudinal adjustment on said rail, a ratchet bar mounted on the other of said cover members, an adjusting bar slidably mounted on said ratchet bar, means connecting said adjusting bar and said anchor bar, a pin carried by said anchor bar for engagement with said apertures and adapted to maintain said anchor bar in any one of a plurality of positions on said rail to maintain said cover members varying distances apart, and a pawl carried by said adjusting bar for engagement with said ratchet bar and adapted to maintain said cover members varying distances apart within the ranges of adjustment of said anchor bar.
3. In a temporary binder the combination of a pair of cover members, a rail mounted on one of said cover members and having a plurality of perforations therein, an anchor bar adjustably mounted on said rail, a rack mounted on the other of said cover members, an adjusting bar mounted on said rack for movement longitudinally thereof, means connecting said anchor bar and said adjusting bar, a detent mounted on said anchor bar for engagement with the perforations therein, a pawl mounted on said adjusting bar for pivotal movement about an axis normal to the plane thereof for engagement with said rack, and means mounted on said adjusting bar for pivotal movement about an axis parallel to the axis of movement of said pawl for releasing said pawl from engagement with said rack.
4. In a temporary binder the combination of a pair of cover members, a rail mounted on one of said cover members and having a plurality of perforations therein, an anchor bar adjustably mounted on said rail, a rack mounted on the other of said cover members,
- an adjusting bar slidably mounted on said rack, means connecting said adjusting bar with said anchor bar, a spring plate mounted on said anchor bar, a pin carried by said plate for engagement with said perforations, a pawl mounted on said adjusting bar for pivotal movement about an axis normal to the plane of said bar for engagement with said rack, a rotatable member mounted on said bar for pivotal movement about an axis parallel to the axis of movement of said pawl for releasing said pawl from engagement with said rack, and a handle mounted on said rotatable member for pivotal movement about an axis transverse to that of the movement thereof and adapted to actuate said rotatable member and for moving said adjusting bar relative to said rack.
5. In a binder the combination with a pair of cover members of an elongated rail secured to one of the cover members and having a plurality of aligned apertures therein, a cross-bar transversely mounted upon the rail and having apertures therein, means on the bar slidably engaging about the rail to mount said bar for guided sliding movement thereon, a spring plate mounted on the cross-bar, a pin carried by the spring plate for engagement through the aperture in the cross-bar and one of the underlying apertures in the rail, and means connecting said cross-bar to the remaining cover member.
